US0D1057141S

(12) **United States Design Patent** (10) **Patent No.:** **US D1,057,141 S**
(45) **Date of Patent:** **** Jan. 7, 2025**

(54) **CAGED CEILING FAN WITH LIGHT**

(71) Applicant: **Shenzhen Anranda Technology Co., Ltd.**, Shenzhen (CN)

(72) Inventor: **Jichang Hu**, Leiyang (CN)

(73) Assignee: **Shenzhen Anranda Technology Co., Ltd.**, Shenzhen (CN)

(**) Term: **15 Years**

(21) Appl. No.: **29/951,910**

(22) Filed: **Jul. 11, 2024**

(51) LOC (15) Cl. **23-04**

(52) U.S. Cl.

USPC **D23/385**

(57) **CLAIM**

The ornamental design for a caged ceiling fan with light as shown and described.

DESCRIPTION

FIG. 1 is a first perspective view of a caged ceiling fan with light showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the caged ceiling fan with light that form no part of the claimed design.

1 Claim, 8 Drawing Sheets
